UNITED STATES PATENT OFFICE.

HENRY A. HAYDEN, OF JERSEY CITY, NEW JERSEY.

SHOE-TREE.

No. 896,536.

Specification of Letters Patent. Patented Aug. 18, 1908.

Application filed September 17, 1907. Serial No. 393,275

To all whom it may concern:

Be it known that I, HENRY A. HAYDEN, a citizen of the United States, and a resident of Jersey City, Hudson county, New Jersey, have invented certain Improvements in Shoe-Trees, of which the following is a specification.

This invention relates to certain improvements in shoe trees such as are particularly designed and adapted for use in boots and 10 shoes for retaining the same in shape, and the object of the invention is to provide a device of this character of a simple and comparatively inexpensive construction which shall 15 be adapted not merely for preserving the shape of the shoe or boot but shall be also possessed of a sanitary function, being adapted to absorb and remove moisture and perspiration from the shoe or boot, whereby the 20 production of offensive odors and deterioration of the leather from such moisture and perspiration are effectively prevented.

The invention consists, in part, in a shoe tree comprising a body portion having a covering of flexible and absorbent or porous 25 fabric and a filling of compressible absorbent material packed therein so that the improved shoe tree is adapted, when in place within a boot or shoe to accommodate itself 30 to the contour of the shoe as modified by the foot during use and is also adapted, by reason of the absorbent or porous nature of the covering fabric, to absorb moisture and perspiration from the boot or shoe.

35 The invention also contemplates certain novel features of the construction, and combinations and arrangements of the several parts of the improved shoe tree, whereby certain important advantages are attained, and 40 the device is rendered simpler, cheaper and otherwise better adapted and more convenient for use all as will be hereinafter fully set forth.

The novel features of the invention will be 45 carefully defined in the claims.

In the accompanying drawings which serve to illustrate my invention—Figure 1 is a perspective view showing a shoe tree embodying my improvements; Fig. 2 is a sectional view 50 taken vertically and longitudinally through the device and showing the detailed construction thereof; Fig. 3 is a sectional view, similar to Fig. 2, but illustrating a modified construction of the improved shoe tree, and— 55 Fig. 4 is another view, similar to Figs. 2 and

3, but illustrating a third modified construction of the device.

The improved shoe tree constructed according to my invention comprises a covering of flexible and absorbent or porous textile 60 fabric such as canvas or the like and is formed from upper and lower portions 1 and 2, joined by seams 3 along opposite sides of the bottom portion 2, said covering being formed to correspond with the contour of the toe 65 portion of a shoe or boot so as to be adapted to be arranged therein in the usual way. At its rear end, the body portion of the device has its covering closed by means of a rectangular piece of fabric 4, stitched along its 70 edges as seen at 5 to the rear ends of the upper and lower portions 1 and 2 of said covering.

6 represents a loop of tape or the like, having its end portions carried through one of the seams 5 and secured as seen at 7 at the 75 lower part of the device. The arrangement of this loop is unimportant and may be varied at will without departure from the principles and spirit of the invention.

8 represents a filling, preferably formed 80 from particles of sponge or other compressible and absorbent material, which filling 8 is tightly packed within the covering of fabric in such a way as to render the same sufficiently compact to permit of retaining the 85 shoe in form when the device is inserted therein in the usual way.

9 represents a reinforce of card-board or other stiff material, preferably of an absorbent character, this reinforce being placed 90 within the body portion of the device at the bottom thereof so as to insure the retention of a flattened formation at the underside of the device to fit snugly against the sole of the shoe throughout substantially the entire 95 width thereof.

10, 10, represent eyelets, set in the fabric from which the covering of the body portion of the device is formed, said eyelets forming 100 ventilating apertures so that the moisture and perspiration collected by the absorbent packing is permitted to be dissipated therethrough when the tree is removed from the shoe. These eyelets 10, 10, may be arranged in any desired manner and may be of any 105 number.

11 represents a block or piece of wood or other resisting material arranged within the body portion of the device at the rear end thereof with a flattened rear surface substan- 110

tially flush upon the rear section 4 of the covering fabric, as shown at 12 in Fig. 2. The forward part of this block or piece 11 is made tapered as clearly shown on the drawing, to 5 adapt it to conform generally to the contour of the improved tree.

In the use of the device constructed according to my invention, the tree is placed within the toe portion of the shoe in the usual manner, after which pressure is applied by means of the fingers upon the rear end of the device, such pressure being communicated to the wooden block or piece 11 which acts as a piston to force the compressible filling or packing 8 into intimate proximity to all parts of the shoe, whereby the flexible body portion is caused to accommodate itself to and to contact intimately with the shoe throughout the entire inner surface thereof so that the 10 shape of the shoe, as modified by the foot of the wearer during use will be faithfully retained. The wooden block or piece 11 is made in a diameter smaller than that of the rear end of the shoe tree, so that the compressible filling 8 is packed around the lateral edges or sides of said block or piece to prevent the same from coming in too close relation to the shoe or boot when the device is in use. Were the said wooden block or piece 15 made of a diameter equal to the larger end of the shoe tree, it is evident that the device could not be inserted in shoes or boots too small to admit said block or piece, but by providing a layer of the compressible filling 20 around the lateral sides of said block or piece, it is evident that the shoe tree may be forced within boots or shoes of sizes smaller than those for which the device is primarily intended. In this way the shoe is prevented 25 from becoming mis-shapen, but the shoe tree being of such a character that it does not tend to preserve the shape of the shoe when new, a great deal of discomfort such as is caused by unyielding shoe trees, particu- 30 larly when permitted to remain for a considerable time in the shoes, is thereby avoided.

The absorbent nature of the body portion of the device, both as regards its covering fabric and filling, insures that the moisture 35 and perspiration which may be present within the shoe after the same has been worn will be removed and absorbed by the improved shoe tree, so that offensive odors are lessened and the deterioration of the leather due to 40 such moisture and perspiration is prevented. The absorbent or porous nature of the covering fabric permits such moisture and perspiration to freely pass through said covering so as to penetrate and be absorbed by the 45 packing or filling 8. The absorbent body portion also forms a vehicle by means of which a suitable disinfectant may be applied to the shoe for overcoming the offensive odors entirely and insuring a sanitary condition. 50

65 For accomplishing this result, the absorbent

body portion may be moistened with any suitable disinfectant fluid, as a dilute solution of carbolic acid in glycerin, and when this shall have become ineffective, a further supply of the disinfectant solution may be applied, being dropped through the ventilating apertures afforded by the eyelets 10.

The improved shoe tree constructed according to my invention is of an extremely simple and comparatively inexpensive nature 75 and is particularly well adapted for use by reason of its compressibility which permits it to adapt itself to the conformation of the shoe and to be held therein without the employment of extraneous means, and also by 80 reason of its absorbent nature which permits of absorbing and withdrawing offensive perspiration and moisture, and it will also be obvious from the above description of my improvements, that the device is susceptible 85 of some modification without material departure from the principles and spirit of the invention, and for this reason I do not desire to be understood as limiting myself to the precise formation and arrangement of the 90 several parts of the device as herein set forth in carrying out my invention in practice. For example, in some cases, the construction shown in Fig. 3 may be employed with good results. As seen in this view, the block or 95 piece 11 is replaced by a wooden disk 14, carried on a stem 15, which protrudes rearwardly from the body portion and is slidable through a gromet 16 set in the rear section 4 of the covering fabric, the rear extremity of 100 said stem 15 having a head or enlargement 17 to be pressed by the hand for manipulating the disk 14 within the covering and thereby compressing the filling or packing 8 to accommodate the body portion to the inner 105 surface of the shoe. Said stem and its enlargement 17 also afford a convenient handle for manipulating the device, and replace the loop 6 of the construction shown in Figs. 1 and 2. The construction shown in Fig. 4 is 110 also well adapted for use, being similar to that seen in Fig. 3, except that the disk 12 is replaced by a wooden block or piece 11 similar to that shown in Fig. 2.

Having thus described my invention, what 115 I claim and desire to secure by Letters Patent is—

1. A shoe tree having a body portion comprising a covering of flexible, porous, absorbent fabric, through which moisture from 120 a shoe is adapted to penetrate, and a filling of compressible absorbent material packed within the said covering and adapted to absorb and retain the moisture penetrating said covering from the shoe.

2. A shoe tree having a body portion comprising a covering of flexible absorbent material, a filling of compressible absorbent material packed within said covering, and a block of resisting material inclosed within 130

the covering at the rear end of the body portion and embedded within the compressible filling material and adapted, when pressed forwardly to exert pressure upon said compressible filling to cause the body portion to conform to the shape of a shoe wherein the device is arranged.

3. A shoe tree having a body portion comprising a covering of flexible absorbent material, a filling of compressible absorbent material packed within said covering, and a piece of resisting material inclosed within the covering at the rear end of the body portion

and embedded within the compressible filling and provided with a stem slidable through 15 said covering and projecting from the rear end of the body portion and forming a handle for manipulating said piece of resisting material within the body portion.

In witness whereof I have hereunto signed 20 my name this 12th day of Sept. 1907, in the presence of two subscribing witnesses.

HENRY A. HAYDEN.
